UNITED STATES PATENT OFFICE.

WALTER EDWIN TRENT, OF WASHINGTON, DISTRICT OF COLUMBIA, ASSIGNOR TO
TRENT PROCESS CORPORATION, OF NEW YORK, N. Y., A CORPORATION OF DELA-
WARE.

PROCESS FOR CONVERTING OR CRACKING HYDROCARBON OILS.

Application filed September 27, 1924. Serial No. 740,383.

The invention relates to improvements in a process for converting or cracking hydrocarbon oils.

The invention more particularly relates to a vapor phase process wherein charging stock is first vaporized in a heat exchanger, and then conveyed to a compressor where said vapors are highly compressed and raised to a cracking temperature for delivery to said heat interchanger to be condensed by the charging stock passing therethrough and to be collected as low boiling point oils.

More specifically, the invention contemplates a process where a portion of the charging stock undergoes vaporization in a heat interchanger, which vapors are then highly heated by a controlled isothermal compression to cause a cracking or conversion of the hydrocarbon vapors producing low boiling point oils, the vapors being condensed in the heat interchanger while the unvaporized residual oil in said chamber is continuously withdrawn as residuum.

In the accompanying drawings I have shown diagrammatically an apparatus capable of supporting this process in which Figure 1 represents the apparatus in diagram.

Referring now more particularly to the drawings wherein like reference characters indicate corresponding parts, the numeral 1 designates a crude oil supply tank having a line 2 leading therefrom to a heat interchanger 3, the oil being fed to the interchanger by a pump 4' or otherwise. The heat interchanger comprises an elongated drum, which is preferably insulated, having a space 4 therein into which the crude oil passes, and interior tubes or passages 5 receiving heated vapors passing therethrough and maintained out of contact with the oil for the purpose of vaporizing a substantial portion of the oil introduced to the heat interchanger.

The crude oil introduced to the heat interchanger is substantially vaporized in the portion 4 thereof, the vapors being withdrawn through the line 6 into a compressor 7 operated by a steam cylinder 8 or the like. The compressor is provided with suitable valves so that the vapors entering said compressor are subjected to a compression of say 100 pounds per square inch before they

can escape. The vapors undergo a controlled compression, which results in a conversion or cracking of the vapors into low boiling point oils. These vapors after this compression then pass through the line 9 into the interior of tubes 5 of the heat exchanger. By passing the hot compressed vapors through these tubes 5 the incoming charging stock or crude oil surrounding the tubes is highly heated to a temperature of say 500° to 600° F., and the compressed vapors are cooled and largely condensed. The condensate representing low boiling point oils passes out through the line 10 from the tubes 5 into the collecting tank 11 from where it is withdrawn and subjected to any approved form of treatment, such as now employed in treating pressure distillate to produce motor fuels.

The temperature of the compressed vapors unless cooled during compression may be excessive and form fixed gases in substantial quantity, and to control the temperature crude oil is circulated by a line 14 through a jacket 15 surrounding this compressor to absorb the excess heat, which oil travels through the line 16 to the charging line 2 entering the heat interchanger.

To start the process the heat interchanger is heated with live steam from a boiler through the tubes 5 to start the vaporization of the charging stock. When vapors of same appear the steam is shut off and the vapors are drawn into the compressor cylinder and from there discharged into the tubes 5. The compressor is constructed to subject said vapors to a compression of a high degree to raise the temperature commensurate with the pressure to give the greatest cracking efficiency, whereupon the vapors discharge into the interior tubes 5 of the heat exchanger. When this stage of an operation has been reached the highly heated cracked vapors passing from the compressor supply sufficient heat in the heat interchanger to raise the temperature of the incoming charging stock sufficiently high to vaporize a substantial portion of such stock. The vapors issue therefrom at about 500° to 600° F. and then pass to the compressor where under a high degree of controlled isothermal compression the vapors are raised to a temperature of say 700 to 950° F., before being permitted to discharge through the

- line 9 to the tubes 5 in the heat interchanger 3. The temperature of the vapors at which they discharge from this compressor is regulated by the passage of charging stock 5 through the jacket surrounding the compressor. It will be understood that the charging stock is vaporized in the heat interchanger under a vacuum whereby the boiling point of the oil is materially lowered so 10 that a substantial portion of this charging stock is vaporized when it reaches a temperature of, say, 500° F. The unvaporized portion is withdrawn through the residual line 2' by pump 2^a into the hot residuum tank 3' continuously where it can be used in any suitable manner. A float valve may be used to maintain the oil level in the interchanger above the residual outlet to prevent the escape of gases.
- 20 The cracked vapors are condensed in the heat interchanger by the cooling effect of the charging stock, and the condensate passes on to the collecting tank for the low boiling point oils.
- 25 In carrying out the process I can utilize any approved form of heat interchanger, whereby the heat of the cracked vapors is utilized to vaporize a substantial part of the charging stock. This operation is preferably carried out under a vacuum in order that the temperatures maintained will cause a vaporization of a very large quantity of the crude oil. Furthermore, any approved type of compressor can be utilized for compressing the vapors to raise the temperature thereof to a cracking degree. The process consists essentially in vaporizing a portion of the charging stock by heat extracted from previously formed vapors that have been compressed isothermally to a cracking condition of pressure and temperature.
- 30 Having thus described my invention, what I claim is:
1. A process of oil conversion, consisting in passing charging stock through a heat interchanger where a portion thereof is va-
- porized, in subjecting said heated vapors to a compression sufficient to raise the same to a cracking temperature, and in passing said vapors to said heat interchanger to supply 50 heat to vaporize the charging stock.
2. A process of oil conversion, consisting in passing charging stock through a heat interchanger where a portion thereof is vaporized while under a vacuum, in subjecting 55 said heated vapors to a compression sufficient to raise the same to a cracking temperature, and in passing said vapors to said heat interchanger to supply heat to vaporize the charging stock.
3. A process of oil conversion, consisting in passing charging stock through a heat interchanger where a portion thereof is vaporized, in subjecting said heated vapors to cracking conditions of temperature and pressure by compression, and in passing said 60 vapors to said heat interchanger to supply heat to vaporize the charging stock and to condense said vapors.
4. A process of oil conversion, consisting 70 in passing charging stock to a chamber where a substantial portion thereof is vaporized, in subjecting the vapors to a high degree of compression sufficient to raise the same to a cracking temperature, in maintaining the temperature to which said vapors are raised substantially constant, in heating the charging stock in said chamber by passage of the cracked vapors therethrough, in withdrawing residual oil from the chamber, 75 and in collecting the converted products.
5. A process of oil conversion, consisting 80 in passing oil through a heat interchanger where a portion thereof is vaporized, in subjecting the heated vapors to cracking conditions of temperature and pressure by compression, and in passing said vapors to the 85 heat interchanger to supply heat to vaporize oil therein.

In testimony whereof I affix my signature.

WALTER EDWIN TRENT.
